SKIRT AND TROUSER RACK

Walter E. Anderson and Elmer A. Anderson,
Chicago, Ill.

Application November 26, 1945, Serial No. 630,819

4 Claims. (Cl. 211—89)

1

The invention relates to improvements in racks and more particularly to skirt and trouser racks embodying novel features of construction and consisting primarily of a pair of identical members independently mounted in close association one with the other to cooperate jointly for the purpose intended.

The best known manner for hanging garments, such as trousers or skirts, is to engage the trouser cuffs or skirt waistband in suitable hangers in such fashion that the trouser or skirt is suspended in a manner so as not to become creased or wrinkled.

Conventional types of racks particularly constructed for use as suspension means for trousers, skirts or like garments frequently are constructed of one piece and, consequently, adjustment of the relative spacing between the garment engaging elements constituting an essential part thereof is impossible. As a result of such constructions the use of racks of that character is restricted to garments of predetermined sizes because should the trouser cuffs or skirt waistband be of insufficient length to bridge the gap between the garment engaging elements, they cannot be suspended therefrom in the manner intended. Likewise, should the trouser cuffs or skirt waistband be of a length greater than the spacing between the engaging elements, the projecting ends thereof sag with the consequent result in the garment becoming wrinkled or otherwise distorted to such an extent as to require pressing before use.

It is, therefore, an object of the present invention to provide a rack of the character referred to which is easily adapted to accommodate garments of any predetermined size.

Other objects of the invention reside in the simplicity of its assembly, the novel low cost construction, and the high degree of effectiveness of the clamping elements thereon.

Other and further objects of the present invention will be apparent from the following description and claims and are illustrated in the accompanying drawing which shows preferred embodiments and the principle thereof and which are considered to be the best modes contemplated for applying that principle. Other embodiments of the invention embodying the same or equivalent principle may be used and structural changes may be made as desired by those skilled in the art without departing from the spirit of the invention or the purview of the appended claims.

In the drawing:

2

Fig. 1 is a perspective view showing the improved rack mounted for use.

Fig. 2 is a longitudinal sectional detail view of one of the arms thereof.

Fig. 3 is a transverse sectional detail view taken on line 3—3 of Fig. 2.

Fig. 4 is a side elevational view of one of a pair of arms constituting a modified form of rack construction.

10 In the embodiment of the invention illustrated in Figs. 1, 2 and 3 of the accompanying drawing, the improved rack consists of a pair of like rack arms, generally indicated at 11, which are arranged in parallel relationship one to the other so as to cooperate for retaining a pair of trousers or skirts or like garments suspended therefrom. Inasmuch as the construction of each of the arms 11 is identical, the description hereinafter will concern itself with the specific details of but one 15 of said arms, it being understood that the description is applicable to the construction of the companion arm.

The rack arm 11 includes an elongated inverted channel 12, preferably fashioned from sheet material such as, for example, steel, having its side walls 13 gradually increasing in width as one end of the arm is approached so as to provide a relatively wide bearing surface at said end to abut a supporting surface 14 upon which the arm is secured. The arm may be secured to such supporting surface as by means of conventional wood screws (not shown) or the like, which are extended through screw openings 15 provided in outwardly turned flanges 16 formed integral with the wide ends of the side walls 13.

A plurality of garment engaging and clamping elements 17 are secured to and depend from the channel 12. As best shown in Fig. 2, these clamping elements may be fashioned from strips of 20 resilient sheet material, such as spring steel or the like, and each is formed substantially U-shaped to define an intermediate portion 18 and depending leg portions 19 and 21. The intermediate portion 18 is suitably apertured to receive therethrough a rivet 22 to firmly secure the clamping element to the top wall 23 of the channel 12. The clamping elements 17 are arranged, as shown, in side by side relationship along the length of the channel 12 and they are suitably spaced apart such distances as to locate one of their leg portions in yieldable abutment with one of the arms with the adjacent clamping element. Thus, it will be seen that when the clamping elements 25 are mounted in place the leg portion 19 of one of said elements is in tight abutment with

the leg portion 21 of the next adjacent element. Such abutment of the leg portions of adjacent clamping elements is insured by initially forming the clamping elements with the arms thereof spread apart a distance greater than the spacing therebetween after they have been mounted in place.

An auxiliary leg portion 21a is provided on the free end of the channel 12 to coact with the leg portion 19 of the end clamping element 17, and similarly, an auxiliary leg portion 19a is provided on the channel 12 inwardly of the innermost clamping element 17 to coact with the leg portion 21 of said element. Each of the auxiliary leg portions 19a and 21a preferably is firmly secured to the channel 12 by means of the rivets 22; the instant disclosure showing an extension 24 on each of said auxiliary arms which lies flat against the inside face of the channel top wall 23 beneath the intermediate portions 18 of the two adjacent clamping elements 17.

Easy insertion of a garment, such as the cuffs of a pair of trousers or the waistband of a skirt, between companion leg portions 19 and 21 is facilitated by extending the free end 25 of each leg portion 21 and 21a at an angle, as illustrated, and the free end of each of the leg portions 19 is similarly bent out of the plane thereof as at 26. It should be apparent that after a garment has been inserted between companion leg portions 19 and 21, it is held firmly therein due to the inherent resiliency of said leg portions and that it may be withdrawn easily and quickly upon being pulled downwardly therefrom.

Obviously, were the clamping elements provided upon a construction which would not permit selective variation of the spacing between the rack arms 11, it would be impossible to properly engage the trouser cuffs or skirt waistband in such a manner as to insure correct suspension thereof. However, due to the separate construction of the two rack arms 11, said arms may be located at any selected spacing dictated by the individual requirements of the user.

A modified form of construction is illustrated in Fig. 4, wherein the rack arm 11a, constituting one of a pair of like arms, is formed of a single piece of material, such as by the molding of plastics or the like, and each arm includes depending companion leg portions 19b and 21b corresponding generally in size and shape to the leg portions 19 and 21 described hereinabove. Each of the leg portions 19b and 21b is resilient and is of such cross-sectional area as to permit them to yield sufficiently to admit a garment therebetween so that the latter may be firmly clamped therein and suspended therefrom.

Although preferred embodiments of the invention have been disclosed in the accompanying drawing and described in detail in the foregoing specification, it should be understood that the invention is capable of embodying a wide variety of modifications without departing from the spirit of the invention or the scope of the appended claims.

We claim:

1. A rack comprising in combination a pair of spaced parallel arms, each of said arms being substantially channel shaped in cross-section, a plurality of inverted substantially U-shaped resilient clamping elements rigidly secured to said arms with the legs thereof depending therefrom and diverging outwardly, the terminal portions of said legs being bent inwardly out of their planes, said clamping elements being uniformly

spaced apart longitudinally of said arms whereby the leg of one clamping element abuts the leg of an adjoining clamping element and coacts therewith to provide tensioned means for receiving and retaining therebetween an article to be supported.

2. A rack comprising in combination a pair of spaced parallel arms, each of said arms being substantially channel shaped in cross-section, a plurality of inverted substantially U-shaped resilient clamping elements rigidly secured to the said arms with the legs thereof depending therefrom and diverging outwardly, one of the legs of each element being substantially longer than the other, the terminal portions of said legs being bent inwardly out of their planes, said clamping elements being uniformly spaced apart longitudinally of said arms whereby the shorter leg of one of the elements abuts the longer leg of an adjoining element and coacts therewith to provide tensioned means for receiving and retaining therebetween an article to be supported, the longer leg serving as a means for guiding the said article between abutting legs to facilitate reception therebetween.

3. A rack arm comprising a channel member, a plurality of inverted substantially U-shaped resilient clamping elements rigidly secured to said member with their legs depending therefrom and diverging outwardly, the terminal portions of said legs being bent inwardly out of their planes, said clamping elements being uniformly spaced apart longitudinally of said arms whereby the leg of one clamping element abuts the leg of an adjoining clamping element and coacts therewith to provide tensioned means for receiving and retaining therebetween an article to be supported.

4. A rack arm comprising a channel member, a plurality of inverted substantially U-shaped resilient clamping elements rigidly secured to said member with their legs depending therefrom and diverging outwardly, one of the legs of each element being substantially longer than the other, the terminal portions of said legs being bent inwardly out of their planes, said clamping elements being uniformly spaced apart longitudinally of said arms whereby the shorter leg of one of the elements abuts the longer leg of an adjoining element and co-acts therewith to provide tensioned means for receiving and retaining therebetween an article to be supported, the longer leg serving as a means for guiding the said article between abutting legs to facilitate reception therebetween.
